Primary Examiner — T Chase Nelson*Assistant Examiner* — Kelly L Gross(74) *Attorney, Agent, or Firm* — Nixon & Vanderhye P.C.(57) **CLAIM**

The ornamental design for a tissue hook for a cricothyrotomy, as shown and described.

DESCRIPTION

FIG. 1 is a front perspective view of a tissue hook for a cricothyrotomy, in accordance with our new design;

FIG. 2 is a top plan view thereof;

FIG. 3 is a bottom plan view thereof;

FIG. 4 is a left side view thereof;

FIG. 5 is a right side view thereof;

FIG. 6 is a front view thereof; and,

FIG. 7 is a rear view thereof.
